UNITED STATES PATENT OFFICE.

JOHN B. WATLING, OF CHICAGO, ILLINOIS.

COIN-CONTROLLED MACHINE.

1,206,958.

Specification of Letters Patent. Patented Dec. 5, 1916.

Application filed February 8, 1916. Serial No. 76,974.

To all whom it may concern:

Be it known that I, JOHN B. WATLING, a citizen of the United States, and a resident of Chicago, county of Cook, and State of Illinois, have invented certain new and useful Improvements in Coin-Controlled Machines, of which the following is a specification.

The invention relates to coin controlled machines and more particularly to coin controlled weighing machines having weight indicating and weight estimating devices and means controlled thereby for returning the coin to the exterior of the machine in case the estimate made by the user is correct. The invention seeks to provide an improved machine of this sort and more particularly to provide locking means for holding the coin returning devices in proper position to return the coin until the latter has passed into the coin return chute or passage way.

A further object is to provide such a locking means which is arranged to be released by the returned coin.

With these and other objects in view, as will presently appear, the invention consists in the features of improvement hereinafter set forth, illustrated in the preferred form 30 in the accompanying drawings and more particularly pointed out in the appended claims.

In the drawings Figure 1 is a front view of the upper portion of the improved machine. Fig. 2 is a rear elevation of the operating mechanism, parts being broken away and the frame and casing being shown in vertical section. Fig. 2^a is a detail elevation of a stop device for the indicating hand or pointer. Fig. 3 is a detail view in front elevation of parts of the operating mechanism. Fig. 4 is an enlarged detail view of the coin chutes within the machine and the means for determining the return or the retention of the coin. Fig. 5 is a detail section on the line 5—5 of Fig. 4. Fig. 6 is a vertical detail section illustrating the manner of mounting the weight indicating and estimating devices or pointers.

The machine is provided with a suitable inclosing casing 1 having, at its upper front portion, a dial 2 over which move the weight indicating and weight estimating hands or pointers 3 and 4. The weighing machine is

provided with the usual base and platform 55 (not shown), the platform being suitably connected to a vertical actuating rod 5.

The upper end of the actuating rod 5 is connected to a heavy spring or springs 5' suspended from a frame work in the upper 60 portion of the machine casing. In the form shown, this frame work comprises two members 6 connected by stay-bolts 7 and mounted on brackets 8 on the side walls of the casing. A shaft 9 is journaled in the upper 65 central portions of the frame members 6 and the weight indicating hand or pointer 3 (see Figs. 1 and 6) is mounted on the forward end of this shaft. A locking wheel 10 is fixed to the shaft 9 and is provided with a 70 series of small teeth which are adapted to be engaged by a beveled or knife-edged locking dog 11 that is fixed to a locking lever 12, the latter being pivoted between its ends upon a lug 13 on the front frame member 6. 75 When the weight indicator is shifted from zero position the locking dog is arranged to engage one of the spaces between the teeth of the locking wheel 10 and thereby secure the shaft 9 against movement with the 80 pointer 3 in proper position to indicate the user's weight. In the normal, zero position of the pointer, the locking dog 11 rests upon a lug 14 that is fixed to and projects from the locking wheel 10 and which is provided with an inclined and a radial or 85 abrupt face. Normally as shown, the locking dog engages the abrupt face thereof to prevent the movement of the indicating shaft in the direction indicated by the arrow in Fig. 2. Preferably, also a second locking dog 15 is pivoted on the front frame member 6 and in the normal zero position of the parts, engages a notch 16 formed in the locking wheel 10. 90

A small pulley 17 is also fixed to the shaft 9 and a cord 18 fixed to and extending over the pulley is provided with a small weight 19. The latter serves to restore the indicating shaft 9 and pointer 3 to zero position and this return movement is limited by a stop device shown in Fig. 2^a. This stop device comprises an arm 20 fixed to the rear end of the indicating shaft 9 and which is arranged to engage a projection on the end 100 of a stop lever 21 that is pivoted between its ends on the rear frame member 6. The opposite end of the stop lever 21 moves be-

tween two stop pins 22 and 23 fixed to the frame member. In the zero position of the indicating pointer and shaft, the lever 21 engages the stop pin 22. If the indicating shaft and pointer are moved through a complete revolution, the engagement of the arm 20 on the shaft 9 would move the lever 21 into engagement with the stop pin 23 and the latter would serve to prevent further movement of the parts.

10 A pinion 24 is loosely mounted on the shaft 9 but a flange 25 fixed to the pinion is provided with a projecting lug 26 that is adapted to engage a lug or pin 27 on the 15 wheel 17 so that a one-way connection is provided between the pinion 24 and the indicating shaft and pointer. The pinion 24 is engaged by a segment rack 28 mounted on the end of an arm 29. The arm is fixed to 20 and projects upwardly from a shaft 30 that is journaled in the lower central portions of the frame members 6. This shaft is provided with a crank arm 31 and an extension arm 32, adjustably fixed to the crank arm, is provided with an actuating weight 33. The weight 33 is considerably larger than the weight 19 and, when a weight is placed upon the platform of the machine, and the locking 25 wheel 10 is released, the weight 33 swings 30 the actuating arm 29 and rack 28 and, through the medium of the pinion 24 and lug 26, rotates the indicating shaft and pointer against the pull of the weight 19. To steady this motion, the shaft 30 is preferably provided with an arm 34 that cooperates with a dash-pot 35 suspended from the frame 6.

35 The actuating arm 29 is held in normal position against a stop 36 by a rod 37 that 40 extends through an opening in a bracket 38 fixed to the upper end of the vertical weight actuated rod 35. A stop collar 39 on the rod engages the upper face of the bracket so that these parts serve to restore the actuating rod 45 29 to normal position when the weight is removed from the platform of the machine. Preferably, the upper end of the rod 37 is 50 adjustably threaded into the end of a link 40 that is pivotally mounted on the crank 55 arm 31, a lock nut 41 being provided for holding the rod in adjusted position.

When the weight is placed upon the platform the rod 5 is depressed and the spring 5' extended to an extent proportionate to 60 the weight. The bracket 38 is also depressed but the other parts remain in the position shown in the drawings until the locking dogs 11 and 15 are released. This is effected by a coin-actuated lever 42 that is pivotally mounted between its ends in a bracket 43, the latter being fixed to the upper central portion of the front frame member 6. One end of the lever is provided with a counterpoise 42' which holds the lever in normal 65 position with the adjacent end engaging a

stop 44. The opposite end of the lever is provided with a coin pan 45 which is normally upheld beneath the end of a chute 46 that leads from a coin slot 47 in the upper front portion of the casing as indicated in Fig. 1.

70 The locking lever 12 is provided at one end with a forwardly projecting lug 48 and at its opposite end with a small counterpoise 49, the latter serving to hold the locking lever in normal position. When a coin is inserted through the slot 47 it passes into the coin pan 45 and depresses the adjacent end of the lever 42. This portion of the lever strikes the projection 48 and also depresses the corresponding end of the locking lever 12 so that the locking dog 11, which is on the opposite end of the locking lever, is lifted out of engagement with the wheel 10. A cord or chain 15' connected to 80 the coin-actuated lever 42 and to the tail of the locking dog 15 also serves to disengage the latter from the wheel 10. If, at this time, there is a weight on the platform, and the bracket 38 is depressed, the indicating 85 hand 3 is rotated as described, until the abutment 39 on the rod 37 engages the bracket 38.

90 At the end of the movement of the lever 42 effected by the coin in the pan 45, the coin 95 is dropped into the upper end of a chute 50 so that the lever is returned to normal position and the locking dogs 11 and 15 again reengage the locking wheel 10 to hold the indicating pointer 3 against movement and 100 also to prevent another weight indication until another coin has been deposited in the machine. But to permit the proper indicating movement of the hand 3, the return movement of the locking and coin actuated levers 12 and 42 is retarded in the usual manner by an escapement mounted on the bracket 43 and comprising a balance wheel 51, a pallet 52 and an escapement wheel 53. An arm 54 fixed to the coin actuated lever 42 is provided with a pawl 55 that cooperates with a ratchet wheel 56 fixed to the escapement wheel. These parts, as usual, are so arranged that the coin actuated shift of the lever 42 is unrestrained 110 but during its return movement it is connected to the escapement wheel 53 and is thereby retarded. At the end of the weight indicating operation the locking dogs 11 and 15 engage the teeth of the wheel 10 and prevent further movement of the wheel. The dog 11 is designed to prevent movement of the locking wheel and indicating parts in either direction while the dog 15 merely serves to prevent further forward movement thereof. 120 When the weight is removed from the platform, the main spring 5' returns the rod 5 and bracket 38 to a normal position and, through the medium of the rod 37 also returns the segment arm 29 and pinion 24. But the in- 125

dicating shaft 9 and pointer 3 remain locked until near the end of the return movement of the bracket 38. At this point the locking dog 11 is disengaged from the wheel 10 so that the indicating shaft and pointer are returned to normal position by the weight 19. During this return movement the dog 15 remains in engagement with the wheel and prevents any motion of the indicating parts in forward direction. At the end of the return movement the inclined portion of the lug 14 passes beneath the locking dog 11 and the parts assume the normal zero position shown in the drawings. To lift the locking lever 12 the bracket 38 is provided with a vertically extending rod 57 (see Figs. 2 and 3), the upper portion of which passes through a guide 58 on a bracket 59, the extreme upper end 23 of the rod having an arm 60 that extends beneath a forwardly projecting lug 61 on the adjacent end of the locking lever 12. The improved weight indicating devices can be operated only once for each coin inserted. The additional locking dog 15 guards any attempts to disengage the main locking dog 11 by jumping on the platform of the weighing machine or scale.

As stated, the coin, after operating the lever 42 drops from the coin pan or holder 45 thereof into the upper end of the chute 50. This chute is provided with an extension 50^a which leads to a cup 62 on the exterior of the casing. A branch chute 63 leads to a coin box or receptacle 64 within the casing. Means is provided for determining whether the coin is returned to the user of the machine or retained within the casing and such means preferably comprises a pivoted deflector plate 64. This deflector plate is fixed at its lower edge to a short horizontal shaft 65 which is mounted in the chute 50 at a point adjacent the junction of the chute 50 with the lower portion of the branch chute 63. A shifter for the deflector plate is provided in the form of a lever 66 which is pivoted adjacent its lower end on a bracket 67 fixed to the side of the chute. The upper end of the shift lever is slotted 50 and engages a crank portion 65^a formed upon the end of the shaft 65. A spring 68 serves to hold the deflector plate in normal position shown in dotted lines in Fig. 2. In this position it extends across and closes the coin-return chute and deflects the coins into the chute 63. By means of the shift-lever 66 the deflector plate may be shifted to the position shown in Fig. 4 so that the coin passing through the chute 50 will be returned to the user of the machine.

A lock is provided for holding the deflector in its shifted position and is preferably in the form of a locking plate 69 mounted on a shaft 70, the latter being journaled in ears 71 formed upon deflector plate

64 adjacent its lower pivoted edge. One end of the shaft 70 projects through a transverse slot in the side wall of the chute 50 and is provided with a crank portion 70^a which is connected to one end of the spring 68, the opposite end of the spring being connected to a lug 72 on the side of the chute. The spring 68 tends to hold the locking plate 69 against a stop piece 73 secured to the adjacent face of the deflector plate 64. The spring also tends to return the deflector plate from its shifted position shown in Fig. 4 back to its normal position shown in Fig. 2, but, in its shifted position the deflector plate is moved against one of the side walls of the chute while the locking plate 69 extends transversely across the chute and engages the opposite side wall and thus securely holds the deflector plate in shifted position until the coin falls through the chute 50 and its extension 50^a. In doing so the coin strikes the locking plate 69, and swings it downwardly so that the spring 68 can act to draw the deflector plate 64 back to its normal position shown in Fig. 2. Means controlled by the weight indicating and estimating devices or pointers 3 and 4 is arranged to operate the shifter 66 and the deflector plate 64 so that when the user's estimate agrees with his actual weight the inserted coin will be returned. Preferably an electro-magnet 74 mounted on the bracket 67 is arranged to shift the lever 66 and the deflector plate and the circuit of this magnet is controlled by two pairs of contacts both of which must be closed to energize the magnet. The weight indicating and estimating pointers 3 and 4 constitute one pair of contacts and preferably, as shown, the weight indicating hand or pointer 3 is provided with a spring contact 75 (see Fig. 6) which is arranged to engage the estimating hand or pointer 4 when both hands or pointers occupy corresponding positions.

The other pair of contacts are formed by a pin 42^a on the coin-actuated lever 42 and a contact arm 76 which is connected adjacent its lower end by a pivot stud 77 to an insulating support 78 on one of the frame members 6 (see Fig. 2.) The lower end of the contact arm or lever 76 is arranged between a pair of stop pins 79 and 80 on the insulating support 78. The upper portion of the contact arm 76 is inclined inwardly and tends to shift by gravity to move its lower end toward the stop pin 79 but, in the normal position of the coin-actuated lever 42 the pin 42^a thereon engages the upper end of the contact arm and holds its lower end adjacent the stop pin 80. The extreme upper end of the contact arm is provided with an insulated portion 76^a which normally engages the pin 42^a so that electrical contact is not formed until a coin is inserted in the machine and the lever 42 depressed thereby.

The lever 42 is so quickly depressed by the coin that the pin 42^a thereon does not have an opportunity of contacting with the uninsulated portion on the arm 76 on the downward movement of the lever. But on the backward retarded movement of the lever 42 the pin 42^a, just before the end of such movement, contacts with the un-insulated portion of the arm 76 and closes the circuit of the magnet 74 at this point.

A swinging inclined plate 81 is arranged in the chute 50 above the deflector plate 64 and is mounted at its upper end upon a short shaft 82 which is journaled in projections on the chute and which is provided with a crank arm 82^a having a small counterpoise 83 thereon. The counter-poise is of such size that it will be overcome by a coin resting on the plate 81 but when a coin is deposited and the lever 42 depressed, the lower insulated end portion 76^b of the contact arm or lever 76 swings over the end of the crank arm 82^a and holds the plate 81 in the position shown in the drawings until the coin drops into the chute 50 and the lever 42 has returned to its normal position. The coin resting on the plate 81 then overcomes the counter-poise 83 and passes downwardly through the chute 63 or into the return chute 50^a in accordance with the setting of the deflector plate 64. By means of the plate 81 the coin is thus retained above the deflector plate until the weight indicating hand or pointer 3 has been shifted to show whether or not the user's estimate is correct.

The user of the machine moves the hand 4 to register his estimate as to his weight by means of a knob 84 on the exterior of the machine casing (see Fig. 1). This knob is mounted on the outer end of a shaft 85 which is provided within the casing with a sprocket wheel 86 and a ratchet wheel 87. The sprocket wheel is connected by a chain 88 to a sprocket wheel 89 that is connected to the estimating pointer 4. As shown in Fig. 6, the pointer 4 is fixed to the outer end of a tube 90 that is surrounded but is spaced apart from the shaft 9. The tube 90 is journaled in a sleeve 91 which is mounted in the bracket 59 but is insulated therefrom by a sleeve 92. The tube is also insulated from the sprocket wheel 89 by a part 93. A spring-pressed friction washer 94 on the outer end of the tubular shaft 90 engages the ends of the sleeves 91 and 92 and serves to hold the estimating pointer 4 in adjusted position. The ratchet wheel 87 (see Fig. 2) which is connected to the sprocket wheel 86 is arranged to be engaged by a spring-pressed locking dog 95. Normally, an arm 96 on the lower end of the rod 57 holds the locking dog 95 out of engagement with the ratchet wheel 87, but when the user is on the platform, the rods 5 and 57 and the part 96 are depressed and the dog 95 engages the

ratchet wheel 90 so that the wheel cannot then further adjust the weight estimating devices.

In operation the user of the machine first adjusts the weight estimating indicator 4 then steps on the platform of the machine so that the rod 5 is depressed against the tension of the spring 5' to an extent proportionate to the user's weight. A coin is then inserted through the slot 47 and the weight indicating devices are released as described and the pointer 3 moves to indicate the user's weight. The coin, as stated, drops into the chute 50 and is arrested by the plate 81. If the estimated and actual weights do not correspond the deflector plate 64 will remain in the normal position shown in Fig. 2 and when the coin is dropped from the detaining plate 81 it will pass into the chute 63 and coin box 64. If the actual and estimated weight, as shown by the pointers 3 and 4 correspond a circuit may be traced from a battery 97 by a conductor 98 which leads to the bushing 91, as shown in Fig. 6, thence by the tubular shaft 90, pointer 4 to the contact 75 and pointer 3, then through the metal frame work of the machine to the lever 42, pin 42^a thereon and arm 76, thus by a conductor 99 to the magnet 74 and by a return conductor 100 back to the battery. The magnet is then energized and the deflector plate 64 shifted to the position shown in Fig. 4. In this position, as described, it is locked by the plate 69 until the coin drops from the detaining plate 81. When this occurs, the coin strikes the locking plate 69, swings it downwardly and passes out to the cup 62 on the exterior of the machine casing. Spring 68 then returns the deflector plate to normal position. As soon as the user of the machine steps off the platform, the spring 5' returns the rod 5 and, through the medium of the rod 37, returns the actuating arm 29 and pinion 24 to normal position. The indicating hand 3 and shaft 9 however, remain locked as stated, until near the end of the return movement of the rod 5 when the parts 57 and 60 connected thereto, lift the locking lever 12. The weight indicating devices are then returned to zero position by the weight 19.

It is obvious that changes may be made in the details set forth without departure from the essentials of the invention as defined in the claims.

I claim as my invention:—

1. In a coin-controlled weighing machine, the combination with weight indicating and weight estimating devices, of a deflector controlled by said devices for determining the retention or return of the coin, and a lock for said deflector adapted to be released by the coin.

2. In a coin-controlled weighing machine, the combination with weight indicating and

weight estimating devices, of a deflector for determining the retention or return of the coin, means controlled by said indicating and estimating devices for setting said deflector to return the coin, and a lock for holding said deflector in set position arranged to be released by the returned coin.

3. In a coin-controlled weighing machine, the combination with weight indicating and weight estimating devices, a deflector normally in position to retain the coin, devices controlled by said indicating and estimating devices for shifting said deflector to return the coin, and a lock for holding said deflector in shifted position, said lock being arranged to be released by the passage of the coin past said deflector to thereby effect the return of the latter to normal position.

4. In a coin-controlled machine, the combination with indicating and estimating devices, of a chute for returning the coin to the exterior of the machine, a deflector normally preventing the passage of the coin through said return chute, means controlled by said indicating and estimating devices for shifting said deflector, and a lock for holding said deflector in shifted position arranged to be released by a coin passing through said return chute.

5. In a coin-controlled machine, the combination with indicating and estimating devices, of a chute for returning the coin to the exterior of the machine, a deflector normally preventing the passage of the coin through said return chute, an electro-magnet controlled by said indicating and estimating devices, means actuated by said magnet for shifting said deflector, and a lock for holding said deflector in shifted position arranged to be released by the passage of a coin past said deflector.

6. In a coin-controlled machine, the combination with indicating and estimating devices and coin-actuated mechanism controlling said indicating device, of a deflector for determining the return or the retention of the coin, means controlled by said coin-actuated mechanism and said indicating and estimating devices for shifting said deflector, and a lock for holding said deflector in shifted position adapted to be released by the coin.

7. In a coin-controlled machine, the combination with indicating and estimating devices and coin-actuated mechanism controlling said indicating device, of a deflector for determining the return or the retention of the coin, means for shifting said deflector, an actuating magnet therefor, a circuit for said magnet controlled by said coin-actuated mechanism and by said indicating and estimating devices, and a coin-released lock for holding said deflector in shifted position.

8. In a coin-controlled machine, the combination with indicating and estimating de-

vices, of a chute for returning the coin to the exterior of the machine, a swinging deflector plate normally closing said return chute, means controlled by said indicating and estimating devices for shifting said deflector plate, and a swinging locking plate for holding said deflector plate in shifted position, said locking plate being arranged in the path of the coin through said return chute and adapted to be released thereby.

9. In a coin-controlled machine, the combination with indicating and estimating devices, of a chute for returning the coin to the exterior of the machine, a pivoted deflector plate normally closing said return chute, means controlled by said indicating and estimating devices for shifting said deflector plate to open said return chute, and a pivoted locking plate for holding said deflector in shifted position, said locking plate being arranged in locking position to extend across said chute and be released by the passage of the coin therethrough.

10. In a coin-controlled machine, the combination of a chute for returning the coin to the exterior of the machine, a pivoted deflector plate normally extending across said chute, means for shifting said deflector plate, and a locking plate pivoted on said deflector plate for holding the latter in shifted position, said locking plate in operative position being arranged to extend across said chute and adapted to be released by the passage of a coin therethrough.

11. In a coin-controlled machine, the combination of a chute for returning the inserted coin to the exterior of the machine, a deflector normally closing said chute, means for shifting said deflector, a lock for holding said deflector in shifted position but arranged to be released by the passage of the coin past said deflector, and means above said deflector for temporarily detaining the coin.

12. In a coin-controlled machine, the combination with a weighing mechanism, an indicator and an indicator shaft, of a pinion loose on said shaft and having a one-way connection therewith to move said indicator from normal position, an actuating arm geared to said pinion, a stop member interposed between said actuating arm and said weighing mechanism, a locking wheel fixed to said indicator shaft, two locking dogs arranged to engage said wheel both in the normal and adjusted positions of said indicator, a coin-actuated trip for temporarily releasing said dogs, one of said locking dogs being arranged to permit the backward movement of said indicator from adjusted position but to prevent the forward movement thereof, and a trip connected to said weighing mechanism for releasing the other of said dogs, substantially as described.

13. In a coin-controlled machine, the com-

bination with a weighing mechanism, an indicator and an indicator shaft, of a pinion loose on said shaft and having a one-way connection therewith to move said indicator from normal position, an actuating arm geared to said pinion, an adjustable stop rod interposed between said actuating arm and said weighing mechanism and having a one-way connection with one of said parts, a locking wheel fixed to said indicator shaft, two locking dogs arranged to engage said wheel to hold said indicator against movement from adjusted position, a coin-actuated trip for temporarily releasing said dogs, one of said dogs being arranged to permit the backward movement of said indicator, and a trip rod for the other of said dogs connected to said weighing mechanism, substantially as described.

14. In a coin-controlled machine, the combination with a weighing mechanism, an indicator and an indicator shaft, of a pinion loose on said shaft and having a one-way connection therewith to move said indicator from normal position, an actuating toothed segment engaging said pinion, an adjustable stop rod interposed between said segment and said weighing mechanism and having a one-way connection with the latter, a locking wheel having a projecting lug thereon, a dog normally engaging said lug, a coin-actuated trip for temporarily releasing said dog, the latter being arranged to engage the teeth of said wheel to hold said indicator in adjusted position, and a trip for said dog connected to said weighing mechanism. 20 25 30 35

JOHN B. WATLING.
